UNITED STATES PATENT OFFICE.

OTTO J. KUHLKE, OF AKRON, OHIO, ASSIGNOR TO THE KUHLKE MACHINE COMPANY,
OF AKRON, OHIO, A CORPORATION OF OHIO.

COLLAPSIBLE CORE OR FORM.

Application filed November 5, 1924, Serial No. 747,913. Renewed August 15, 1927.

This invention relates to collapsible cores or forms for the building of pneumatic automobile tires, which are characterized by the provision of collapsing mechanism which is permanently attached to the several form sections so that the form may be collapsed and assembled with rapidity and ease. It is a purpose of the invention to improve upon prior constructions for this general purpose and to devise a simple, inexpensive and easily operated device.

In the drawings there is shown one form or embodiment of the invention, it being understood that the showing is for the purpose of illustrating principles of the invention and not for limiting the invention beyond the fair scope of the appended claims.

In the drawings:

Figure 1 is a side elevation of the core in assembled condition;

Figure 2 is a similar view showing the core at the termination of the first collapsing movement;

Figure 3 is a section on the line 3—3 of Figure 1;

Figure 4 is a section on the line 4—4 of Figure 2;

Figure 5 is a plan view of the core in collapsed position; and

Figure 6 is a section on the line 6—6 of Figure 1.

This application is a continuation as to common subject matter, of my prior application, Serial No. 735,265, filed September 2, 1924.

The core of the present invention is characterized and distinguished from prior core constructions in that it makes use of a single key section which is supported at a fixed distance from the core shaft or support, while the remainder of the core sections, which are connected together to form a unit, are moved toward and from the axis of the core so as to carry the completed tire away from the key section. It is also characterized by the fact that the unit of core sections is movable in a substantially straight line in an oblique direction to the plane of the core, so that the sections will shift to a position outside of but parallel to the original core plane. When the sections carrying the tire have been removed as described, certain of the sections are folded inwardly, being hinged for that purpose to a centrally located or rigid section, the movement of

the core sections being about inclined or oblique hinges so that the sections move toward the center of the core and also outwardly of the plane thereof. The hinging of the movable sections is so arranged that one section will fold over the other hinged section. When the several core sections have been moved as indicated, the tire is stripped from the core, which may then be reassembled.

The central core shaft or support is indicated by the numeral 1, which may be the shaft of the tire machine or tire stand. On the end of the shaft is secured a central plate 2, the face of which is inclined at an oblique angle to the plane of the core and one edge of which is provided with a rack 3. The upper end of the plate is formed with a yoke 4 provided with two lugs 5 to which is secured the stationary key section 6 which, in the present embodiment of the invention, is rigidly mounted.

Upon the front of the plate 2 is mounted a movable slide or supporting plate provided with flanges 8 which embrace the plate 2 and by which the unit referred to above is guided so as to be movable in an oblique direction with respect to the original core plane. In order to move the slide 7 over the central plate, a pinion 9 is mounted in the slide in position to engage the rack, being provided with suitable means by which it can be rotated. A spring operated pin or dog 10 is secured in the slide and is adapted to engage holes 11 and 12 in the central plate to lock the group of core sections in assembled and collapsed position, respectively.

The sections of the core, other than the rigid key section, are carried by the slide 7, and are constituted by a plurality of sections 14, 15, and 16, of which intermediate section 15 is rigid, being attached to the slide 7 by means of lugs 17 formed thereon. The sections 14 and 16 are hinged to the intermediate section so that they can be swung inwardly. The preferred form of hinge is indicated at 18, the hinge being arranged so that each section, in moving inwardly toward the center of the core, will also move outwardly from the plane of the core. The position of the swinging sections is shown in Figure 5, in which the section 14 is moved inwardly first and the section 16 is then moved so as to overlap or rest upon the

section 14. It will be observed that for this purpose the hinges 17 are arranged at oblique angles to the plane of the core.

5 Keys 19 may be provided between the free ends of the sections 14 and 16 and the key section.

10 The operation of the device will be readily understood. When the tire is completed upon the core and is ready to be stripped therefrom, the operator, having withdrawn the pin 10, will enter the hole 12 and lock them in the position shown in Figure 2. The remainder of the core is now free of the key section and the sections 14 and 16 15 may be swung inwardly and the tire removed.

It is obvious that changes and modifications may be made in specific embodiments of the invention. The number and arrangement of the core sections may be altered and the manner of hinging the swinging sections upon the central or fixed section may be changed. Other variations may be introduced within the scope of the invention as will be understood by those skilled in the art.

30 It will be understood that certain principles of the invention may be applied to tire building forms of varying shapes and are not necessarily limited to the rounded core section. Where the term "core" is used throughout the specification and claims, it will be understood that the term is used broadly and may cover any tire building 35 form.

What is claimed is:

1. In a collapsible form, a key section, means to support the key section at a fixed distance from the form support and a plurality of sections hinged together and constituting a unit, and means to move the unit toward and from the form axis and angularly with respect thereto.

45 2. In a collapsible core, a stationary key section and a plurality of sections hinged together and constituting a unit, and means to move the unit toward and from the core axis and obliquely with respect thereto.

3. In a collapsible core, a stationary key 50 section and a plurality of sections constituting a unit, and means for moving the unit toward and from the axis of the core in an oblique direction.

4. In a collapsible form, a key section and a plurality of sections constituting a unit, the unit being movable in a fixed path toward and from the axis of the form in an oblique direction relative to the original form plane.

5. In a collapsible core, a plurality of core sections less than the total number of sections to complete the core, said core sections being movable as a unit, and a guide for said unit arranged at an oblique angle with respect to the original core plane.

6. In a collapsible core, a plurality of core sections constituting a portion of the core and forming a unit, and a guide arranged at an angle to the original core plane and over which the unit is movable while remaining parallel to the original core plane.

7. In a collapsible core, a plurality of core sections constituting a portion of the core and forming a unit, and a guide arranged at an oblique angle to the original core plane and over which the unit is movable.

8. In a collapsible form, a plurality of form sections constituting a portion of the form and forming a unit, a guide arranged at an oblique angle to the original form plane, and means to move the unit upon the guide.

9. In a collapsible core, a plurality of core sections constituting a portion of the core and forming a unit, a guide arranged at an oblique angle to the original core plane, means to move the unit upon the guide, and means to lock the unit at the limits of its movement.

10. In a collapsible core, a stationary section and a plurality of sections which are hinged together and constitute a unit, a guideway for said unit arranged at an oblique angle to the plane of the core, and means for moving the unit along said guideway toward and from the axis of the core.

11. A collapsible core composed of a plurality of core sections, a supporting plate for the core, one of the sections being a key section and carried by the plate, the remaining sections being hingedly connected together as a group, a guiding formation on the plate and diverging from the plane of the core, and means carried by the group of sections having sliding engagement with the formation.

12. A collapsible core comprising a plurality of core sections, a supporting plate for the core, certain of said core sections being hinged together as a group, a guiding formation on the plate and diverging from the plane of the core, and means carried by the group of sections having sliding engagement with the formation.

13. A collapsible core comprising a core section, an arm attached to the core section and projecting toward the center of the core but diverging therefrom, said arm supporting the core section for sliding movement and intermediate core sections pivoted to 120 and carried by the first named section.

14. A collapsible core comprising a core section, an arm attached to the core section and projecting toward the center of the core but diverging therefrom, and an additional core section hinged to one end of the first named core section, the arm supporting the core sections for sliding movement.

15. A collapsible tire building form comprising a plurality of form sections which

are hinged together in a group, a central supporting plate for the form, and means to support the group of sections for sliding movement upon the plate.

5 16. A collapsible tire building form comprising a plurality of form sections which constitute a group and are angularly hinged together, a central supporting plate for the form, and means to support the group of 10 sections for sliding movement upon the plate.

17. A collapsible form comprising a form section, an arm attached to the form section and extending in an angular direction 15 toward the axis of the form, and a second form section carried by the first named form section.

18. A collapsible form comprising a form section, means to support the form section 20 for movement in a fixed path toward the axis of the form in an angular direction, and a second form section carried by the first named form section.

19. A collapsible core comprising a core 25 section, a guiding arm attached to the core section and extending in an angular direction toward the axis of the core, a second core section carried by the first named core section, and a third core section supported independently of the other sections.

20. A collapsible core comprising a core section, a guiding arm attached to the core section and extending in an angular direction 35 toward the axis of the core, two core sections carried by the first named core sections, and a remaining section supported independently of the other sections.

21. A collapsible core construction embodying a core section, means for guiding 40 the core section in a fixed path at an angular direction toward the core axis, and additional core sections hinged to the ends of the first named section, the hinges being at an angle to the original core plane.

45 22. A collapsible core construction em-

bodying a core section, means for guiding the core section in a fixed path at an angular direction toward the core axis, and a second core section hinged to the end of the first named section, the hinge being at an 50 angle to the original core plane.

23. In a collapsible form construction, a key section, means for securing the key section in fixed relation to the form support, and a group of form sections, means for 55 moving the group of form sections toward and from the center of the form, and guiding means for the group.

24. In a collapsible form construction, a key section, means for securing the key section in fixed relation to the form support, and a group of form sections movable toward and from the center of the form, and 60 guiding means for the group.

25. In a collapsible form construction, a 65 stationary key section, and group of form sections which are hinged together, and means for moving the group of form sections relatively to the key section.

26. In a collapsible form construction, a 70 stationary key section, a group of form sections which is composed of a rigid section and swinging sections pivoted thereto, and means for moving the group of form sections toward and from the center of the 75 form.

27. In a collapsible form construction, a stationary key section and a group of form sections which comprises a rigid section and a swinging section pivoted thereto, and 80 means for moving the group of form sections toward and from the center of the form.

28. In a collapsible form construction, a 85 form shaft, a plate secured thereon, a key section on the end of the plate, a group of form sections, and a slide movable over the plate to which the group is attached.

OTTO J. KUHLKE.
